Patented Oct. 21, 1958

183,766

PORTABLE EVAPORATIVE COOLER

Gordon D. Petrie, Phoenix, Ariz., assignor to Wright Mfg. Company, Phoenix, Ariz., a corporation of Arizona

Application November 13, 1957, Serial No. 48,444

Term of patent 14 years

(Cl. D62—4)

Fig. 1

Fig. 2

Fig. 3

Fig. 4

Fig. 1 is a front perspective view of a portable evaporative cooler incorporating the features of my design;

Fig. 2 is a top plan view of the portable evaporative cooler shown in Fig. 1;

Fig. 3 is a side elevation of the portable evaporative cooler taken from the left of Fig. 4, the opposite side being the same in appearance except for the knob element;

Fig. 4 is a front elevation of the portable evaporative cooler, the rear being substantially the same in appearance.

I claim:

The ornamental design for a portable evaporative cooler, as shown.
